UNITED STATES PATENT OFFICE.

ERNEST EISENHUT, OF GALION, OHIO, ASSIGNEE, BY MESNE ASSIGNMENTS, TO CENTRAL OHIO STEEL PRODUCTS COMPANY, OF GALION, OHIO, A CORPORATION OF OHIO.

AUTOMATIC DUMPING TRUCK.

Application filed February 3, 1925. Serial No. 6,608.

This invention relates to dumping trucks, and particularly to those dumping wagons where the body is mounted for rocking movement upon the frame or chassis of the truck, 5 the body being tilted by positive manually operable means and brought to its horizontal position after discharging its load by a positive manually operable means.

One of the objects of the present invention 10 is to provide manually operable means for positively tilting the body from its horizontal position to its discharge position, which will include means absorbing the shock of the chassis caused by the arrest of the dumping action.

A further object is to provide means not only acting to shift the body to its dumping position but acting to hold and lock the body at the maximum dumping angle until released.

A still further object is to provide manually operable means for tilting the body which will furnish the initial movement to cause the return of the body to its road or horizontal 25 position, and further in this connection to automatically lock the body in its horizontal or road position on its return.

Another object is to provide means for releasing and giving an initial impulse to the body toward its horizontal or road position and releasing the body to permit it to oscillate to its tilted position, which is operated by a lever disposed adjacent the driver's seat and which may be operated without the driver 30 turning around, which operating lever may also be pulled to cause the return of the body to its horizontal or road position.

Still another object is to provide a body which is automatically locked in its road position without reliance on pins, plugs or springs, and in general to provide a fully automatic gravity dumping body having the features heretofore set forth.

Other objects will appear in the course of 45 the following description.

My invention is illustrated in the accompanying drawings, wherein:—

Figure 1 is a fragmentary side elevation of a dumping truck showing my mechanism applied thereto, the body being lowered;

Figure 2 is a like view to Figure 1 but with the body raised;

Figure 3 is an enlarged elevation of the prop and the actuating means therefor with the body lowered;

Figure 4 is a top plan view of a portion of the iron 44 and the body operating means attached thereto;

Figure 5 is a like view to Figure 3 but showing the prop extended;

Figure 6 is a fragmentary elevation of the latch showing its engagement with the bolt operating lever;

Figure 7 is a fragmentary rear elevation of the prop and shaft therefor;

Referring to these drawings, it will be seen that I have illustrated such portions of a dumping truck as are necessary for a clear idea of the construction and operation of my invention, and that in these drawings 10 designates the longitudinal beams of the chassis, these beams being preferably channel iron. Mounted upon the beams at their rear ends or supported in any suitable manner is an approximately U-shaped angle iron 11, and at the rear ends of the arms of the U-shaped angle iron there are parallel short irons 12 and a plurality as, for instance, three transverse pins 13. The dumping body 14 is provided with a pair of sector-shaped members 15 having teeth which mesh with the spaces between the pins 13, and these sector-shaped members and the teeth constitute a fulcrum upon which the dumping body tilts. I do not wish to be limited to this, however, as any other means for pivotally or tiltingly supporting the dumping body 14 may be provided.

The forward end of the body 14 is provided with a depending counterweight 16 mounted upon the dumping body in any suitable manner, and attached to this counterweight, which has a width less than that of a dumping body, and to the inside face thereof is a keeper or locking member 17 having a base and an upwardly and rearwardly extending lip 18. Mounted upon the beams 10 just rearward of the normal position of the counterbalance 16 is a shaft 19 which is, of course, mounted in suitable bearings, and

keyed to this shaft and normally extending downward therefrom at one end of the shaft is a short operating arm 20. This arm is connected by a longitudinally extending link 21 to a hand lever 22 mounted upon a suitable supporting bracket 23 and located adjacent the driver's seat. Also mounted upon this shaft 19 is a latch, designated generally 24, this latch being formed to provide a hook-shaped portion 25 which engages over the keeper 18 and a rectangular head 26 having a surface disposed at an angle of approximately 45° to the horizontal plane, this surface extending upward and forward.

15   Mounted upon the forward end of the truck body behind the counterbalance 16 is a tubular casing 27 which is pivoted at 28 between ears 29 and which is open at its lower end, and operating through this casing is a rod 30 carrying a collar 31 at its inner end which operates against a coiled compression spring 32 disposed within the casing, this spring bearing at its lower edge against a flange 33 immediately surrounding the connecting rod 25 or link 30. This link or connecting rod 30 at its end remote from the body is pivotally connected at 31^a to an arm 34 which is loosely mounted upon the shaft 19 for independent oscillation. This arm at its end adjacent the rod 30 is angularly off-set, as at 35, and bifurcated to receive the extremity of the rod 30. The extremity of the rod 30 is rounded and formed at one point with a notch 36, and mounted upon the upper face of the arm 34 is a locking rod 37 whose extremity is adapted to engage in the notch 36 and which is urged in this direction by a spring 38, this rod being mounted in guides 39 and being actuated by means of a link 40 which is pivoted thereto and whose other end is pivoted to an angular or bell crank lever 41 mounted upon the arm 34 and specifically between the two sections of this arm, this arm being formed in two parallel sections held to each other by bolts 42 and held apart by spacing sleeves or like means.

50   The flat bars or sections which constitute this arm 34 at their forward ends are spread apart to embrace and be disposed on each side of that portion of the latch 24 which is mounted upon the shaft 19, as illustrated in Figure 7. Surrounding the shaft 19 is a coiled spring 43, which at one end is attached to this shaft and at the other bears against a transversely disposed angle iron 44 having a stop 45. The spring, therefore, urges the shaft in a counterclockwise direction.

55   It will be obvious now that when the shaft 19 is turned so as to bring the arm 34 and the link 30 into line, as illustrated in Figure 2, that the latch bolt 37 will slip into the notch 36 and thus lock the two sections of the prop in approximate alignment with each other and with the body tilted, and under 60 these circumstances it is impossible for the

prop formed of the two sections to "break" but that when the locking bolt is retracted the two sections of the prop may break and fold upon each other to permit the body to return to its initial position.

65   The operation of this mechanism is as follows: Assuming that the body is turned into a horizontal position, as shown in Figure 1, then a pull on the hand lever 22 by the truck operator operates through connecting rod 21 to impart an oscillatory movement to the shaft 19. This causes the latch 24 to move rearward, withdrawing it from engagement with the keeper 18. As soon as the latch is withdrawn from the keeper 18, force of gravity causes the body to tilt upon its fulcrum and the load to be discharged. As the body tilts from the horizontal to its dumping position, it causes the sections 30 and 34, which really constitute two links, to straighten out from an angular position with relation to each other into or toward a straight line position, and when the body reaches its predetermined maximum dumping angle the pivotal points 19, 31^a and 28 are approximately 70 in the same line and the two sections or links are approximately in line with each other. Therefore, the further movement of the tilting body is arrested. Inasmuch as the dumping body is connected to the link or rod 30 by the spring housing 27 and the spring therein, it follows that the shock caused by the sudden cessation of the dumping movement is transmitted through the spring housing to the spring 32 which is, therefore, compressed so that the shock is expended against this spring.

75   As the body comes to rest at the maximum dumping angle, the latch bolt 37 is forced by the spring 38 into the notch 36, preventing further rotation of the parts around the pivot 31^a. The two portions of the prop formed by these two sections 30 and 34 are thus locked in approximately the same line, preventing any further movement of the body.

80   If now it be desired to return the body to its normal position, then a pull is exerted on the hand lever 22. This operates through the connecting rod 21 to impart an oscillatory movement to the arm 20 which is transmitted through the shaft 19 to the main latch 24, causing this latch to move rearward. As it moves rearward, the head 26 of this latch will strike the bell crank lever 41 and turn this bell crank lever on its pivot, thus causing the withdrawal of the bolt 37 from the notch 36. This movement continues until the inclined outer face of this latch 24 comes in contact with both arms of the bell crank lever 41, as shown in Figure 6, which locks this bell crank lever so it can no longer move and at the same time locking the arm 34 to the main latch so that as the main latch moves downward and rearward, a downward and rearward movement of the lower section 34 or 85

arm will be produced and a positive mechanical action will be thus caused tending to give an initial return impulse to the body to cause it to return to its road or horizontal position.

5 This movement of the hand lever has been secured against the action of the spring 43 and, therefore, as soon as the hand lever is released the spring 43 operating through the shaft 19 will bring the arm 20 back against the stop 45, preventing the travel of the main latch 26 beyond its proper location for engagement with the latch hook or keeper 18. As the body returns to its road position through the gravity action of the counter-
15 balancing apron 16, the beveled surface on the lower face of the latch hook 25 comes in contact with the inclined surface of the upper side of the main latch or keeper 18, forcing the main latch backward until the locking surfaces are in alignment. Then the spring 43 operating through the shaft 19 forces the main latch into complete engagement with the keeper, securely locking the body in road position.

20 It is to be noted at this point that the fulcrum for the body is a shifting fulcrum, that when the body is in a horizontal position the supporting point or fulcrum is nearest to the forward end of the body and, therefore, the rear end of the body is the heaviest so that the counterbalancing action is such as to urge the body to a tilted position. As the body tilts or moves toward its fully upright position, the fulcrum shifts rearward until when the body is fully tilted the fulcrum is nearer to the rear end of the body than it is to the forward end but the body is held in its tilted position at this time by the prop composed of the two sections 30 and 34. Therefore, when these two sections are unlatched there is a tendency on the part of the body to return to its horizontal position, and when the lever 22 is pulled quickly back it acts to throw the latch 24 rearward, release the locking bolt 37 and almost instantaneously bring the bell crank of the locking bolt to the position shown in Figure 6 and give a slight downward and rearward movement to the section 34. As soon as this slight downward movement is given the hand lever is released and the latch 24 returns under the action of the spring to its initial position, but the impetus given to the link or section 34 is sufficient to transmit impetus to the dumping body to cause it to move downward rapidly, which movement is accelerated by the counterbalance on the forward end of the body. As the body shifts to its horizontal position, the fulcrum shifts forward also, as heretofore explained. Thus it will be seen that while this mechanism might be applied to a truck having a tilting body not mounted upon a shiftable fulcrum, yet there is an intimate coaction between the shifting fulcrum and the prop with the actuating means therefor, in that when the body is in its horizontal po-

sition gravity urges the body to a tilting position, and when the body is in its tilted position gravity urges it back to a horizontal position.

It will be seen that the principal feature of the entire mechanism is that it provides in a unitary device means for holding the dumping body locked in its raised position, means for releasing the locking means for holding the body at a dumping angle, and means for returning and locking the body in its road position while the operator at all times maintains his correct driving position. This mechanism is such that it does not make it necessary for the operator to turn around, reach in back of his seat, or dismount entirely in order to release the lock, and furthermore in my mechanism the dumping body is automatically and securely locked at the dumping angle until the operator himself causes its release. Furthermore, with this mechanism the initial impulse to return movement is automatically and mechanically given and the mechanism has a self-contained shock absorber and holds the lock in proper position for engagement on the return and at all times when not released by a positive movement on the part of the operator. Furthermore, with this mechanism the operator is required not to push upon this handle but to pull upon the handle and the pull upon the handle when the body is in its road position causes the release of the body in its dumping position and a like pull upon the operating handle when the body is in a tilted position will cause the body to return to its horizontal position.

It will be seen that this mechanism has no pins or plugs to become worn or rusted so that they cannot be removed, has no exposed springs, and no delicate trip devices. It will be further seen that the starting movement for dumping the body is given by the release of the lock by the operation of the hand lever, which, when the body is in dumping position, by the same operation gives movement, sufficient with the adjusted balance, to cause the body to return to horizontal position.

While I have illustrated certain details of construction and arrangement of parts which I have found to be particularly valuable in practice, I do not wish to be limited thereto as it is obvious that many changes might be made without departing from the spirit of the invention as defined in the appended claims.

I claim:—

1. In a vehicle, a chassis, a tiltable body mounted thereon, means for holding the body tilted including a prop formed in two sections pivoted to each other at their approximate ends, the sections being respectively pivoted to the body and to the chassis, one of said sections including a barrel, and a plunger operating within the barrel, and a spring contained within the barrel and against which the plunger operates as the two sections of the

prop move into approximately aligned position and the body nears its fully tilted position.

2. In a vehicle, a chassis, a tilttable body thereon, means for holding the body tilted and limiting its tilting movement including a prop formed in two sections pivoted to each other at their proximate ends, the sections being pivoted to the body and to the chassis, releasable means normally holding the body lowered and the prop folded, a lock carried by one of the sections and adapted to lock the sections in approximate alignment when the body is fully tilted, and a single manually operable means operatively connected to said holding means to cause the release thereof when the manually operable means is actuated to thereby permit the body to shift to a tilted position, said releasable holding means adapted to operatively engage said lock to release the same when the body is in its tilted position and to give an initial impulse of retraction to the sections of the prop.

3. In a vehicle, a body mounted upon a fulcrum and tending when in a horizontal position to move to a tilted position and when in a tilted position tending to return to its horizontal position, means acting to support the body in a tilted position, single means adapted to automatically engage the body when the body has approximately reached its horizontal position to hold the body in said horizontal position and if the body be in a tilted position acting when shifted in one direction to release said supporting means and give an initial return impulse to the body, and manually operable means for shifting said single means in a direction to give said initial return impulse.

4. In a vehicle, a chassis, a body swingingly mounted thereon for movement from a horizontal to a tilted position, a prop formed in two sections pivoted to each other and respectively pivoted to the chassis and to the body and when shifted into angular relation to swing into a convergent position toward the rear end of the body, a spring actuated latch adapted to engage the body as it moves from a tilted to a horizontal position and hold the body in a horizontal position, and manually actuatable means operatively connected to said latch to shift the latch from its engaging position and permit the tilting of the body, said latch operatively engaging one section of said prop to cause the sections to move from an aligned position to thereby permit the body to move downward and thereby give an additional return impulse to the body.

5. In a vehicle, a chassis, a body mounted thereon for tilting movement and tending, when in a horizontal position, to move to a tilted position and when in a tilted position tending to return to a horizontal position, a latch pivotally mounted upon the chassis, a

keeper mounted upon the body and with which the latch is adapted to automatically engage when the body has reached its horizontal position, means for holding the body in a tilted position including sections pivoted to each other and respectively pivoted to the chassis and to the body and when the body is tilted being disposed in line with each other and limiting the tilting movement of the body, means locking the sections in approximate line with each other, manually operable means for shifting said latch rearward to permit the movement of the body into a tilted position to discharge its load, and means actuated by a further movement of the latch under the action of said actuating means acting to unlock said sections and positively shift the sections out of approximate alignment with each other to thereby give an initial return impulse to the body and permit the downward movement of the body.

6. In a vehicle, a chassis, a body mounted upon the chassis for tilting movement from a horizontal to an inclined discharge position, a latch mounted on the chassis and adapted to automatically engage the body as the body nears its horizontal position and lock the body in this horizontal position, a prop formed in two sections pivoted to each other, the sections being respectively pivoted to the chassis and to the body and adapted, when in line with each other, to hold the body in its inclined position against downward movement, and a manually actuatable controlling member movable in one direction to first release the latch and upon a further movement to cause the latch to operatively engage one section of the prop to thereby shift the sections rearward out of alignment with each other and permit the sections to fold as the body descends to a horizontal position.

7. In a vehicle, a chassis, a body mounted upon the chassis for tilting movement from a horizontal to an inclined discharge position, a latch mounted on the chassis and adapted to automatically engage the body as the body nears its horizontal position and lock the body in this horizontal position, a prop formed in two sections pivoted to each other, the sections being respectively pivoted to the chassis and to the body and adapted, when in line with each other, to hold the body in its inclined position against downward movement, and a manually actuatable controlling member movable in one direction to first release the latch and upon a further movement to cause the latch to operatively engage one section of the prop to thereby shift the sections rearward out of alignment with each other and permit the sections to fold as the body descends to a horizontal position, one of the sections of the prop having elastic means yieldingly limiting the degree of inclination of the body.

8. In a vehicle, a chassis, a body pivotally mounted upon the chassis for movement from a horizontal position into an inclined position and vice versa, a latch member swingingly mounted upon the chassis, a keeper on the body with which the latch member is adapted to engage, a spring urging the latch member into a position where it will engage the keeper, a manually actuatable member 5 operatively connected to the latch member to shift it rearward and out of its locking position, a prop formed in two sections pivotally connected to each other and respectively pivoted to the chassis and to the body, a 10 spring actuated locking bolt carried by one of said sections and adapted to engage with the other section to thereby lock the two sections in approximate aligned position, a lever connected to the locking bolt and shiftable in one direction to release it, said lever being disposed in the path of movement of the latch when the body is in a tilted position and the latch is moved rearward, the latch becoming operatively engaged with the section 15 when the bolt has been retracted to thereby shift the section rearward to thus cause the prop to break and to transmit an initial downward impulse to the body, and a spring returning the latch to its initial position.
9. In a vehicle, a chassis, a tiltable body thereon, means for holding the body tilted and limiting its tilting movement including a prop formed in two sections pivoted to each other, the sections being respectively pivoted 20 to the body and to the chassis, a bolt carried by the lowermost section and adapted to engage the uppermost section when the sections are in approximate alignment with each other and the body is tilted to thereby hold the prop from breaking, the bolt having an angular 25
- lever pivoted to the lowermost section, a latch pivotally mounted upon the chassis and having a head formed with an inclined face, a keeper mounted upon the body and adapted to be engaged by the latch, an actuating member operatively connected to the latch whereby it may be shifted, and a spring urging the latch into the path of movement of the keeper, the head of the latch, when the latch is shifted rearward and the two sections of the prop are in approximate alignment with each other, engaging the lever connected to the bolt and shifting the lever to withdraw the bolt and then engaging the lever to cause a unitary movement of the lower section and 30 of the head of the latch rearward to thereby break the prop and give an initial downward impulse to the body, said spring acting to return the latch to its normal position as soon as the actuating member is released. 35
10. In a vehicle, a body mounted upon a fulcrum and tending when in a horizontal position to move to a tilted position and when in a tilted position tending to return to its horizontal position, means acting to support 40 the body in a tilted position including a prop formed in two sections pivoted to each other at their meeting ends, one of said sections being pivoted to the body and the other to the chassis of the truck, a lock carried by 45 one section and automatically engaging the other section when the two sections of the prop are in aligned position and the body is tilted, and manually operable means shiftable in one direction to engage said lock and 50 retract it and give an initial return impulse to the body.

In testimony whereof I affix my signature.

ERNEST EISENHUT.
